Primary Examiner — David G Muller*Assistant Examiner* — Christina Gabrielle Cosden(74) *Attorney, Agent, or Firm* — Olive Law Group, PLLC(57) **CLAIM**

The ornamental design for a smart door lock, as shown and described.

DESCRIPTION

FIG. 1 is a top, front and right side perspective view of a smart door lock showing my new design;
FIG. 2 is a top, rear and right side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.
The broken lines show the portions of the smart door lock that form no part of the claimed design.

1 Claim, 8 Drawing Sheets(56)
